[57] **CLAIM**

The ornamental design for a combined hair curler and heating unit, as shown and described.

DESCRIPTION

FIG. 1 is a front perspective view of a combined hair curler and heating unit embodying my new design; FIG. 2 is an exploded perspective view thereof; FIG. 3 is a right side elevational view of the heating unit shown separately for ease of illustration; FIG. 4 is a top plan view thereof; FIG. 5 is a rear elevational view thereof; FIG. 6 is a left side elevational view thereof; FIG. 7 is a front elevational view thereof; FIG. 8 is a bottom plan view thereof; FIG. 9 is a right side elevational view of the hair curler, shown separately for clarity of illustration; FIG. 10 is a front end elevational view thereof; FIG. 11 is a rear end elevational view thereof; and, FIG. 12 is an elevational view thereof, rotated 180 degrees from FIG. 9.
